(57) **CLAIM**

The ornamental design for a surgical instrument handle, as shown and described.

DESCRIPTION

FIG. 1 is a front, left, and top isometric view of a surgical instrument handle.

FIG. 2 is a rear, right, and top isometric view of the surgical instrument handle.

FIG. 3 is a left elevation view of the surgical instrument handle.

FIG. 4 is a right elevation view of the surgical instrument handle.

FIG. 5 is a rear elevation view of the surgical instrument handle.

FIG. 6 is a front elevation view of the surgical instrument handle.

FIG. 7 is a top plan view of the surgical instrument handle; and,

FIG. 8 is a bottom plan view of the surgical instrument handle.

The broken lines are included for the purpose of illustrating the portions of the surgical instrument that form no part of the claimed design.

1 Claim, 4 Drawing Sheets
